Primary Examiner — George D Kirschbaum*Assistant Examiner* — Jennifer Watkins(74) *Attorney, Agent, or Firm* — Ryan D. Levy; Patterson Intellectual Property Law, P.C.(57) **CLAIM**

What is claimed is the ornamental design for a training station, as shown and described.

DESCRIPTION

FIG. 1 is a front perspective view of the training station of Applicant's invention.

FIG. 2 is a front elevation view of the training station of Applicant's invention.

FIG. 3 is a right elevation view of the training station of Applicant's invention.

FIG. 4 is a back elevation view of the training station of Applicant's invention.

FIG. 5 is a left elevation view of the training station of Applicant's invention.

FIG. 6 is a top elevation view of the training station of Applicant's invention; and,

FIG. 7 is a bottom elevation view of the training station of Applicant's invention.

The portions of the article placed in broken lines in the drawing illustrate a symbol that is a registered trademark of the company Move Strong Functional Fitness Equipment, LLC and forms no part of the claim.
